Application March 29, 1938, Serial No. 198,789

10 Claims. (Cl. 183—7)

The present invention is concerned with devices in electrical precipitators for mechanically operating hammers used to jar accumulated loose material from the electrodes.

8 Rapping the electrodes with hammers or other similar means to jar off the accumulations is normally carried out as an intermittent operation done at regular intervals that may vary in length from a few minutes to an hour or more in typical cases, depending on the rate of accumulation. The hammers are operated in some installations by hand, but this is a difficult, tiresome job and is usually done inefficiently. When manual operation is relied on, the intervals between 10 rapping are frequently too long and the precipitator efficiency is lowered. Also the expense is objectionably high since a workman cannot do any other useful work in the intervals between the short periods of operation which seldom exceed from fifteen to thirty seconds.

Effective rapping requires a series of sharp, heavy blows of the hammers delivered against anvils associated with the electrodes, all blows being preferably of uniform weight. The period of 25 contact of the hammer and anvil is also preferably as short as possible, because when grounded hammers are used to rap the high tension discharge electrodes, the electrodes are grounded and rendered inoperative while the hammer is in 30 contact with the anvils. A rapid advance of the hammer followed immediately by a rapid reverse movement delivers the desired type of sharp blow and also reduces to a minimum not only the time of contact and non-operation, but also the time 35 that the hammers are within arcing distance of the electrode. This characteristic of the hammer motion cannot be obtained in previous types of hammer operating mechanisms which have a rigid connection between the power source and 40 the hammer because the connecting linkage either holds the hammer against the electrode anvil for a short time which contact damps the vibrations set up in the electrode, or else delivers an ineffective blow.

45 Mechanical hammer actuating mechanisms are preferably flexible in use and operation so that they can be installed on precipitators originally equipped with manually operated hammers and can in case of emergency be operated by hand. 50 Also they should be easily adapted to automatic operation at predetermined regular intervals or at irregular intervals under the control of an operator.

55 Thus it is a general object of my invention to provide a mechanism for operating hammers in

a manner to deliver a short, sharp blow that is effective to dislodge accumulated material and to keep the hammer in contact with the electrode anvils, or near it, for only a minimum length of time.

It is also a principal object to provide hammer operating mechanism that has a yielding or resilient connection at some point between the prime mover and the hammer in order to assure a quick return movement of the hammer and to 10 easily regulate the strength of blow delivered.

Another object is to provide hammer operating mechanism in which the hammers return to a normal rest position out of contact with the anvils regardless of the position of the rest of 15 the mechanism when rapping is stopped.

An additional object of my invention is to provide a mechanism for operating hammers that is adapted to swing hammers against two anvils alternately and that is readily adjustable to 20 equalize the strength of alternate blows and control the strength or weight of the blows.

A further object is to provide a hammer actuating mechanism that is easily and inexpensively built and operated either as an original installation or as an improvement to manually 25 operated hammers.

It is also an object to provide in conjunction with a device for mechanically operating hammers, means operable by the device to reduce the 30 current flow through the high tension discharge electrodes while they are being rapped.

These objects of my invention are accomplished by providing in an electric precipitator having one or more electrodes associated with an 35 anvil, one or more hammers adapted to be swung against the anvil, and hammer actuating mechanism comprising a driving member, a driven member, and a resilient connection between these two members. The driving member rotates or 40 reciprocates and imparts a reciprocating motion to the driven member through the resilient connection, which may be a pneumatic cylinder forming an air cushion, a spring, or other similar energy storing means. A connecting means, preferably articulated and inelastic, connects the driven member to the hammer to drive it, the hammer in my preferred form having an oscillating motion.

The strength of the blows delivered is regulated by means regulating the degree of compression of the resilient connection, thus a valve controlled fluid by-pass is used on the pneumatic cylinder and movable abutments are used with the springs.

When there are two spaced anvils in one precipitator, the hammers are mounted between the anvils and swing against the anvils alternately. Although the regulating means mentioned above can in some forms be used to at least partially equalize the blows on both anvils, it is preferred in many instances to provide counterbalancing means that is adjustable to fully equalize the impact on both anvils.

Because of the unusual and exacting requirements for a mechanism used to rap the high tension electrodes, I shall describe my invention in that aspect, but it will be readily apparent that the invention may be used equally well with hammers rapping the collecting electrodes since the general construction is very similar though the operating requirements are not as exacting.

How the above and other objects and advantages of my invention are attained will be more easily understood by reference to the following description and the annexed drawings, in which:

Fig. 1 is a fragmentary view, partly in elevation and partly in vertical section as on line 1-1 of Fig. 2, of a typical electric precipitator showing hammer actuating mechanism constructed according to my invention;

Fig. 2 is a vertical section on line 2-2 of Fig. 1;

Fig. 3 is an enlarged fragmentary view illustrating in detail the construction of the pneumatic cylinder which is shown partially in elevation and partially in section;

Fig. 4 is an enlarged fragmentary section of the gas-tight bearing for the connecting rod attached to the hammer shaft;

Fig. 5 is a wiring diagram;

Fig. 6 is a vertical section of a variational form of resilient means comprising springs for driving the piston; and

Fig. 7 is an elevation partly in section of a variational form of pneumatic cylinder.

There is illustrated in Figs. 1 and 2 a portion of a typical, large scale electrical precipitator of the type used commercially to precipitate dust and other foreign particles from a stream of gas; and the showing of this particular precipitator is to be considered merely as illustrative of one application of my invention since the invention may be readily adapted to other types of precipitator construction. The precipitator includes a structural frame indicated generally at 10 and a gas-tight housing 11 attached to the frame members so that no gas will escape to the atmosphere as it passes through the precipitator for treatment. The collecting electrodes, which are grounded, may be of any suitable construction, but the "rod-curtain" type electrode 14 herein illustrated is typical of commercial practice and is composed of a row of vertically extending rods 15 spaced at short intervals along angle 16 by which the rods are supported from one of the frame members 10. It will be understood that one unit of a precipitator normally includes a number of such collecting electrodes placed side by side and parallel to each other, but suitably spaced apart so that the dust-laden gas flows between the electrodes and in a direction parallel to their horizontal extent.

In each interval between two collecting electrodes is located a high tension discharge electrode 18 which is composed of a number of fine wires 19 or sharp-edged rods supported from a pipe 20 extending parallel to and midway between two collecting electrodes. Consequently, there are also a number of discharge electrodes, as may be seen from Fig. 2, all of similar construction

and extending in the direction of gas flow. These collecting and discharge electrodes are opposed to each other and form together one section or unit of the entire precipitator. A number of such units may be placed in series so that the gas flows through them in succession; and Fig. 1 shows adjacent portions of two successive units. Pipes 20 are bolted at each end to a channel 21, and all the discharge electrodes of one unit are supported from a pair of channels 21 which each rest upon brackets 22 riveted to posts 24, of which there are two at each end of a unit though only one is shown. A pair of these posts 24 are supported from cross channel 25 which rests at each end upon a column of insulators 26 to electrically insulate the high tension discharge electrodes and their supporting structures from the rest of the precipitator. Where posts 24 and channel 25 pass through openings in interior partitions as at 27 and 28 respectively, means are provided for eliminating exposed sharp corners to prevent arcing over from the high tension parts to the grounded precipitator frame.

Although most of the material precipitated out of the gas stream settles upon the collecting electrodes, yet a portion of the dust or foreign particles collects upon discharge wires or rods 19 of the high tension electrodes and it is necessary periodically to jar or vibrate these electrodes in order to free them of accumulated material that, if left on the electrodes, greatly reduces their electrical efficiency. In order to accomplish this jarring or rapping action, one or more disk-like hammers 30, attached to the ends of arms 31, are swingingly supported from rock shaft 32 that extends parallel to channels 21. Although one hammer 30 may be sufficient, it is preferred to provide several of them on a single shaft. Rock shaft 32 is rotatably mounted in bearing brackets 33 depending from frame members 10, and all the parts being normally of metal, the hammers are grounded through the shaft and bearings. However, it is within the scope of my invention to make shaft 32 of electrically insulating material in whole or in part, or insulated from frame 10, in which case the hammers are not grounded and cannot short out the high tension electrode.

The rock shaft is so placed at one end of a precipitator unit that, when it is rocked, hammers 30 swing upwardly and outwardly from their normal rest position below shaft 32 and strike against channels 21, one hammer being shown at 30a in Fig. 1 at the time of contact with the right hand channel. The impact of the hammer blow against channel 21 jars all of pipes 20, which rest on pins 21a that are rigidly attached to the channel, and shakes the discharge wires 19 sufficiently to free them of accumulated material. When shaft 32 is placed mid-way between two units of the precipitator as shown in Fig. 1, the same set of hammers alternately strike against two channels 21, one at each side of the shaft and belonging to different units.

Because channels 21 receive the blows delivered by the hammers, these channels are termed anvils; but it will be realized that any suitable member associated with one or more electrodes in such a way as to transmit the blow to the electrodes when struck by a hammer may be used as an anvil and it is not necessary to use for this purpose one of the electrode supports. Anvils of the general type shown are used when a single anvil can be used to rap a series of electrodes. When the hammer raps only one elec-

trode, it may strike against a portion of the electrode especially shaped or reinforced to receive the hammer impact; and this portion may be considered to be included in the scope of the term anvil as used herein. In either construction, the anvil is electrically part of the electrode because of the impracticability of electrically insulating the anvil from the electrode.

The resilient connection between the driving and driven member of the mechanism for actuating the hammers is pneumatic cylinder 34 which is illustrated in detail in Fig. 3. The cylinder comprises a cylindrical housing 34c closed at both ends by cylinder heads 35, the two heads being securely drawn down against the ends of housing 34a by nuts on the ends of tie rods 36 which pass through the cylinder heads. Within cylinder 34 is the driven member, piston 37, which is provided at each face with a leather cup 38 to form a fluid-tight seal between the piston and the cylinder walls as the piston reciprocates within and relative to the cylinder. Piston rod 40 is attached to piston 37 by pins 41 and preferably extends through both cylinder heads. This construction is preferred because it affords a double bearing for the piston rod and eliminates any tendency of the piston to bind within the cylinder, and also because the net surface on each side of the piston exposed to air pressure within the cylinder is made equal. Each cylinder head 35 is supplied with a packing gland 42 through which piston rod 40 slides.

For reasons that will be more evident, there is provided means for permitting restricted air flow between the chambers formed in the ends of the cylinder at the opposite sides of piston 37. This means preferably is in the form of an external fluid by-pass 44 which is connected at each end to a fluid passage 46 in a cylinder head 35 that communicates with the cylinder interior in order that air may flow from one end of the cylinder, around piston 37, to the other end of the cylinder. A manually operable valve 45 of any suitable conventional style is placed preferably in by-pass 44 so that the flow of fluid through the by-pass may be regulated or completely cut off as may be desired. Natural leakage of air around piston 37 may be relied on or a fluid passage may be placed in piston 37 instead, but the external passage 44 is preferred because it is easily regulated in effective size by an adjustable valve.

Cylinder 34 is connected at its upper end by bracket 48 to the outer end of the drive means, crank 49, which is rotated by drive shaft 50 of an electric motor 51. Motor 51 is supported at the proper height on a platform structure 52 erected above the precipitator housing.

The lower end of piston rod 40 carries clevis 54 and pin 55 which pivotally joins the piston rod to the upper end of connecting rod 57. Connecting rod 57 has secured at its lower end, arm 58 which is pivotally connected at 59 to arm 60 on rock shaft 32. Piston rod 40, connecting rod 57, and arm 60 together form an inelastic articulated connecting means for drivingly connecting piston 37 to the hammers 30 so that reciprocation of the piston causes shaft 32 to rock and swing the hammers against anvils 21, as will be more fully explained.

From inspection of Fig. 1 it will be evident that the motion of the lower end of rod 57 has both horizontal and vertical components in the plane of the drawing, but that at a point near the upper end of the connecting rod this motion may be reduced to a vertical motion and a rocking

motion about a horizontal axis perpendicular to the plane of the drawing. Advantage is taken of this fact to provide a gas-tight bearing and seal near the upper end of the connecting rod where it passes through housing 11 to the exterior thereof. Connecting rod 57 is partly enclosed by portion 11a of the precipitator housing, which is surmounted by casting 64, shown in greater detail in Fig. 4. The upper end of casting 64 has a vertical bore 65 across which extends 10 cylindrical bearing 66, the bearing having a gas-tight fit with its cylindrical seat in casting 64 but being sufficiently free to rock about its horizontal axis. Bearing 66 is held in place against endwise movement by a removable plate 67 on 15 the vertical face of casting 64. Rod 57 has a snug sliding fit within a vertically extending bore in bearing 66. This construction allows shaft 57 to move freely in a longitudinal direction and to rock about the axis of bearing 66 which seals the 20 interior of the precipitator against gas loss around the exit of the connecting rod through the precipitator housing.

More satisfactory operation is obtained by using some equalizing or counterbalancing means 25 to equalize the force supplied through connecting rod 57 on both up and down strokes. A preferred type of means for this purpose includes arm 70 mounted to swing about fulcrum 71 intermediate the ends of the arm. At one side of 30 the fulcrum 71, arm 70 carries weight 72 slidingly mounted on the arm and provided with set screw 73 to lock the weight in any adjusted position. At the other side of the fulcrum, the arm is pivoted to the connection means between the piston and shaft 32, and this is easily accomplished by passing pin 55 of clevis 54 through the forked end of the arm, as illustrated in Fig. 3. The necessary longitudinal movement of arm 70 to accommodate the horizontal movement of pin 55 is afforded by placing fulcrum 71 at the upper 35 end of post 75 which is pivotally mounted on bracket 76 secured to precipitator housing 11. Arm 70 may be used as a handle for operating the hammers manually, valve 45 being opened 40 to make the work easier.

The operation of the hammer actuating mechanism will be more readily understood if it is assumed that valve 45 of by-pass 44 is initially wide open so that air may flow freely from one 45 end of cylinder 34 to the other end. Under these conditions, rotation of crank 49 by drive shaft 50 causes the pneumatic cylinder to reciprocate vertically with respect to piston 37, but the air within the cylinder displaced by the relative 50 movement of piston 37 merely flows to the opposite end of the cylinder through the by-pass and no pressure is built up within the cylinder. The result is little or no vertical movement of piston 37 from its normal rest position and piston rod 40 merely swings about pin 55 which remains 55 practically stationary.

As valve 45 is slowly closed, the restriction to fluid flow through the by-pass causes the air in the lower portion of the cylinder to become compressed to some extent during the upward movement of the cylinder, and the air in the upper portion of the cylinder to become equally compressed during the downward movement of the cylinder. The air pressure thus applied alternately to opposite faces of piston 37 tends to drive it in the same direction as the cylinder, and thus raises and lowers rods 40 and 57. This reciprocating movement of the connecting rods rocks shaft 32 and swings hammers 30 from their 60

normal rest position out toward anvils 21. As valve 45 is progressively closed, a point is reached at which the pressure within cylinder 34 is sufficient to swing hammers 30 just into contact with one or both of anvils 21, but no blow of any appreciable force is delivered.

When no counterbalancing means are provided, it would normally be found at this point that hammers 30 swing higher to the right in Fig. 1 than to the left, principally because the weight of the vertically moving parts 31, 40, 51, and 58 adds to the force of crank arm 49 on the downward stroke. The weight of cylinder 34 also adds to the force imparted by crank 49 on the 15 down stroke in the same manner but to a smaller degree. It is to overcome this unbalanced effect that the counterbalancing means is provided; and, with the mechanism shown, the vertically reciprocating parts are counterbalanced by moving 20 weight 72 out on arm 70 to the point at which hammers 30 swing equally to each side. The proper position for weight 72 is most readily determined if the weight is set when the hammers just contact anvils 21 at the end of each stroke. 25 Having made this adjustment, valve 45 is now closed still further to greatly restrict fluid flow in by-pass 44 and obtain the desired weight or strength of blow against anvils 21. If leather cups 38 form an absolutely air-tight seal with 30 the walls of the cylinder, then valve 45 will usually be slightly open when the desired force is obtained from hammers 30; but if there is a material amount of leakage past the piston, then this may be sufficient and valve 45 can be entirely closed without causing too heavy a blow. 35

The force of the blow delivered by the hammers is also controlled by both the speed of revolution and the throw of drive crank 49. Assuming the stroke of the piston to be equal to the 40 maximum vertical movement of pin 59 and the frequency of reciprocation to be equal to the natural period of hammers 30, no impulse is delivered to the piston by movement of the cylinder except for the natural lag in movement of the hammer 45 caused by friction within the system. Under these circumstances there is almost no relative movement of the cylinder and piston and they move practically as a unit; and of course a minimum of energy is required since the only power 50 consumed in keeping the hammers swinging at their natural period is that required to overcome friction losses. To increase the power delivered to the piston and correspondingly increase the energy of the hammer blows, either the stroke 55 may be lengthened by changing the length of crankage or the frequency increased by changing the speed of motor 51, or both.

In practice it has been found satisfactory to 60 use a throw of crank 49 approximately equal to, but slightly greater than, the throw required were crank 49 connected rigidly to piston rod 40, and a frequency approximately one-third greater than the natural period of the hammer. 65 Since the piston reciprocates faster than the natural period of the rest of the system, the relative movement of the piston and cylinder compresses the air between the piston and the cylinder ends. The energy stored in this compressed air is delivered to the piston and transmitted through the connection means 40, 51 and 60 to shaft 32 and hammers 30. Naturally the cylinder always leads the piston, so that at the moment of impact of the hammers the piston is already tending to 70 reverse the direction of hammer movement and 75

the sole energy of the blow delivered is from the compressed air and momentum of the hammers. The resilient connection between the driven piston 31 and drive crank 49 afforded by the pneumatic cylinder eliminates any direct force from the driving member tending to hold the hammers in contact with the electrode anvils and consequently reduces the duration of contact between hammer and anvil to a minimum. Immediate disengagement of the hammer and anvil prevents any damping action by the hammer and allows the electrode to vibrate freely under the impact of the blow. The resilient connection also takes up any over-travel of the cylinder caused by it having a longer stroke than the piston. 15

Regardless of the position of crank 49 when the rapping action is stopped, hammers 30, because of their weight, always return to their normal rest position shown by the full lines of Fig. 1. Counterbalance 72 neutralizes, or approximately so, the effect of the weight of parts 40, 51, and 58 on the position of the hammers which thus assume substantially a position directly beneath shaft 32 and midway between anvils 21. Leakage of air either through by-pass 44 or past piston 31 permits the weight alone of the hammers to move piston 31 and restore them to their rest position. This characteristic automatically insures that the hammers will not remain within arcing distance of the discharge electrodes or 30 anvils between periods of rapping.

As previously mentioned, hammers 30 are normally grounded to the frame of the precipitator whereas anvils 21 and the high tension electrodes are electrically insulated from the precipitator frame; but this is not the case during the short instant that the hammers contact the anvils, for during the contact the discharge electrodes are also grounded through the hammers. For this reason the duration of contact is made as short 40 as possible because when so grounded the discharge electrodes are rendered inoperative.

It is preferred to provide means for reducing the current in the high tension system during the period of rapping in order to reduce the tendency 45 to arc over to the hammers as they approach and recede from the anvils, though such means can be omitted entirely if the hammers are used to rap low tension collecting electrodes. One arrangement for accomplishing this is illustrated in Fig. 5 in connection with a typical wiring diagram. A transformer 80 supplies high tension alternating current to rectifier 81 which converts the current supplied to discharge electrode 18 to unidirectional current. The collecting electrodes 14 are grounded. In the power supply circuit to the low tension side of transformer 80 is an alternate branch circuit having a resistance 82 placed in parallel with the regular conductor 83, and switch 84 by which the power current may be supplied through either circuit branch 82 and 83. Switch 84 is operated by relay 85 in the electric circuit to motor 51 so that when motor 51 is running in order to drive the hammer actuating mechanism, relay 85 moves switch 84 to the position shown to divert the transformer current through the resistance 82. When motor 51 is shut off, relay 85 ceases to operate and switch 84 automatically is returned to position to supply current through conductor 83. Though the relay 70 shown is current operated, a voltage operated relay connected across the motor terminals can be used as well. The electric circuit to motor 51 may be controlled by any type of switch mechanism either manually or automatically operated. 75

and the switch indicated at 88 is of a rotary type readily adapted to mechanical operation so that the intermittent rapping operation may be automatically brought about after any desired interval of time.

Fig. 6 illustrates a variational form of mechanism to replace the pneumatic cylinder, in which springs are used instead of compressed air to afford a resilient connection between the driving member, crank 49, and the driven member, the piston and piston rod 40. This mechanism comprises housing 88 within which piston 89 reciprocates, the piston being attached to rod 40 by a pin 90. On either side of piston 89 and bearing thereagainst is a compression spring 91 which is held within the cylinder by abutment plate 92. Plates 92 are preferably individually adjustable with respect to housing 88, and for this purpose are here shown as threaded and screwed into an internal thread 88a in housing 88 so that the compression of each spring 91 can be individually adjusted. Lock nuts 93 hold abutment plates 92 in adjusted positions. Plates 92 also provide two spaced bearings for rod 40 and guide the piston 25 to prevent binding.

Housing 88 is preferably a cylinder and closed at both ends in order to properly confine springs 91 and to exclude dirt from the springs and piston 89. However, an open cage may be used to connect the two abutments 92 if desired, and any other suitable form and shape may be given to the driven member 89. When the closed housing shown is used, it is preferred either to make piston 89 a loose fit in the cylinder or to provide ports 94 in the piston to prevent compression of the air by the piston travel. Housing 88 is connected to crank 49 in the same way as cylinder 34, bracket 48a being suitably modified to permit fastening it to the upper end of the housing.

The operation of the hammer is substantially the same as already described, the springs 91 being a resilient driving connection between drive crank 49 and driven piston 89 and one that stores energy in the same general manner as the compressed air at the ends of cylinder 34. Adjustment of the force of the strokes delivered to the driven member is accomplished by changing the position of abutments 92, the length of threads 88a determining the range of adjustment; and if threads 88a are sufficiently long, movement of the cylinder can be made to produce no movement of the piston, just as when valve 45 is fully open. Since plates 92 are individually movable, the compression of springs 91 can be individually adjusted to make the force of the up and down strokes unequal and in this way some of the counterbalancing formerly done only by weight 72 can be done.

Fig. 7 illustrates a variational form of pneumatic cylinder equipped with two fluid by-pass lines 44, 44a controlled separately by a valve 45, 45a in each by-pass. In addition, each by-pass has a check valve 96, 96a of any conventional style, such as a ball or flap type, and so not shown in detail. As indicated by the arrows on the valves, air flow is in opposite direction in the two lines, as for example down only in the left hand one and up only in the right hand one. By closing valves 45, 45a different amounts to produce unequal restriction to fluid flow in the two by-pass lines, a greater pressure can be built up at one end of the cylinder than at the other, and, neglecting other considerations, more force can be given to the piston on one stroke than the other. If right hand valve 45a is closed more

than the other valve 45, the upward movement of the cylinder produces a higher compression in the lower end of cylinder 34 than is produced in the upper end of the cylinder by its downward movement. The excess in the force thus applied is made sufficient only to lift the vertically reciprocating rods 40 and 57 and offset the added force imparted to the hammers from their weight when they move downwardly. Although the greater force of cylinder 34 is delivered on the down movement, the lesser pressure in the upper end of the cylinder offsets this, and consequently the force of the hammer blows on the two anvils can be regulated individually as desired, and can be made approximately equal.

Having described certain specific forms of my invention it will be understood that various changes in construction and arrangement of parts may be made without departing from the spirit and scope of my invention; and for this reason, the foregoing description is to be considered as illustrative of rather than restrictive upon the appended claims.

I claim:

1. In an electric precipitator having an electrode and an anvil associated therewith enclosed within a gas-tight housing, externally actuated mechanism for rapping the anvil to jar loose precipitated material accumulated on the electrode, comprising a hammer mounted for movement into contact with the anvil from a normal rest position out of contact with the anvil; drive means; a driven member; resilient energy storing means, mounted exteriorly of the gas-tight housing and drivingly connecting the drive means and the driven member; articulated connection means connecting the driven member and the hammer to swing the latter against the anvil; said articulated connection means comprising a lower rod and an upper rod pivotally connected to the lower rod; and a gas-tight bearing through which the lower rod extends from the interior to the exterior of the housing, said lower rod being mounted for longitudinal and rocking movement in the bearing.

2. In an electric precipitator having a plurality of electrodes and a pair of spaced anvils associated therewith, mechanism for rapping the anvils to jar loose precipitated material accumulated on the electrodes, comprising a hammer disposed between the anvils and mounted to swing into alternate contact with the two anvils from a normal rest position out of contact with either anvil; a pneumatic cylinder closed at both ends; a piston within the cylinder and movable relative thereto; drive means connected to and actuating the cylinder; connection means drivingly connecting the piston to the hammer to swing it against the anvils; and counterbalancing means attached to said connection means for equalizing the blow of the hammer on each anvil.

3. In an electric precipitator having an electrode and an anvil associated therewith enclosed within a gas-tight housing, externally actuated mechanism for rapping the anvil to jar loose precipitated material accumulated on the electrode, comprising an anvil secured to an electrode; a hammer mounted for movement into contact with the anvil from a normal rest position out of contact with the anvil; a pneumatic cylinder closed at both ends and mounted exteriorly of the gas-tight housing; a piston within the cylinder and movable relative thereto; a rotatable crank connected to and reciprocating said cyl-

inder relative to the piston to compress air between the piston and the ends of the cylinder; and articulated connection means connecting the piston to the hammer to swing the hammer 5 against the anvil, said articulated connection means comprising a lower rod and an upper rod pivotally connected to the lower rod; and a gas-tight bearing through which the lower rod extends from the interior to the exterior of the gas-tight housing, said lower rod being mounted for longitudinal and rocking movement in the bearing.

4. In an electric precipitator, the combination of a high tension discharge electrode; an electrode anvil, a grounded hammer mounted on the precipitator frame and adapted to strike a blow against the anvil to jar the electrode, the hammer normally occupying a rest position out of contact with the anvil; means for actuating the hammer; an electric motor driving said hammer actuating means; a transformer supplying high tension current to the discharge electrode; a resistance in an alternate branch of the low tension circuit of the transformer; and a relay operable by the power supply to the motor to divert the low tension circuit of the transformer through said resistance when the motor is driving the hammer actuating mechanism.

5. In an electric precipitator having a plurality of electrodes and a pair of spaced anvils associated therewith, mechanism for rapping the anvils to jar loose precipitated material accumulated on the electrodes, comprising a hammer disposed between the anvils and mounted to swing into alternate contact with the two anvils from a normal rest position out of contact with either anvil; a pneumatic cylinder closed at both ends; a piston within the cylinder and movable relative thereto; drive means connected to and actuating the cylinder; connection means drivingly connecting the piston to the hammer to swing it alternately against the two anvils; and counter-balancing means attached to said connection means for equalizing the blow of the hammer on each anvil, comprising a pivoted arm and a weight adjustably positioned on the arm.

6. In an electric precipitator having a plurality of electrodes and a pair of spaced anvils associated therewith, mechanism for rapping the anvils to jar loose precipitated material accumulated on the electrodes comprising a hammer disposed between the anvils and mounted to swing into alternate contact with the two anvils from a normal rest position out of contact with either anvil; a pneumatic cylinder closed at both ends; a piston within the cylinder and movable relative thereto; drive means connected to and actuating the cylinder; a fluid by-pass interconnecting the ends of the cylinder at opposite sides of the piston; a valve in the by-pass adjustably restricting fluid flow through the by-pass; and connection means drivingly connecting the piston to the hammer to swing it alternately against the two anvils.

7. In an electric precipitator having a plurality of electrodes and a pair of spaced anvils associated therewith, mechanism for rapping the anvils to jar loose precipitated material accumulated on the electrodes, comprising a hammer disposed between the anvils and mounted to swing into alternate contact with the two anvils from a normal rest position out of contact with either anvil; a pneumatic cylinder closed at both ends; a piston within the cylinder and movable relative thereto; a fluid by-pass interconnecting the ends

of the cylinder at opposite sides of the piston; a valve in the by-pass adjustably restricting fluid flow through the by-pass; a rotatable crank connected to and reciprocating said cylinder relative to the piston to compress air between the piston and the ends of the cylinder; articulated means drivingly connecting the piston to the hammer to swing it alternately against the two anvils; and counterbalancing means attached to said connection means for equalizing the blow of the hammer on each anvil.

8. In an electric precipitator having a plurality of electrodes and a pair of spaced anvils associated therewith, mechanism for rapping the anvils to jar the electrodes comprising a hammer disposed between the anvils and mounted to swing into alternate contact with the two anvils from a position out of contact with either anvil; a pneumatic cylinder closed at both ends; a piston within the cylinder and movable relative thereto; drive means connected to and operable to reciprocate the cylinder; connection means drivingly connecting the piston to the hammer to swing the hammer into alternate engagement with the respective anvils; two separate fluid by-pass means each interconnecting the ends of the cylinder at opposite sides of the piston; and independently adjustable valve means associated with each fluid by-pass means and operable individually to adjust the driving force exerted on the piston upon movement of the cylinder in each direction.

9. In an electric precipitator having a plurality of electrodes and a pair of spaced anvils associated therewith, mechanism for rapping the anvils to jar loose precipitated material accumulated on the electrodes, comprising a hammer disposed between the anvils and mounted to swing into alternate contact with the two anvils from a normal rest position out of contact with either anvil; drive means; a driven member; resilient energy storing means drivingly connecting the drive means and the driven member; connection means drivingly connecting the driven member and the hammer to move the latter against the anvils, the connection means and the driven member being disposed to move generally vertically whereby the weight of the parts when moving downwardly increases the force of the blow against one anvil and when moving upwardly decreases the force of the blow against the other anvil; and counter-balancing means attached to said connection means and operating to exert a force opposing downward movement and assisting upward movement of the connection means and the driven member to equalize the blows on each anvil; said counter-balancing means including means for adjusting the counter-balancing force.

10. In an electric precipitator having a plurality of electrodes and a pair of spaced anvils associated therewith, mechanism for rapping the anvils to jar loose precipitated material accumulated on the electrodes, comprising a hammer disposed between the anvils and mounted to swing into alternate contact with the two anvils from a normal rest position out of contact with either anvil; a pneumatic cylinder; a piston reciprocable within the cylinder; a rotatable crank reciprocating the cylinder relative to the piston; a piston rod extending through one end of the cylinder and secured to the piston; connection means operatively connecting the piston rod to the hammer, the connection means and the piston rod being disposed to move generally verti-

cally whereby the weight of the parts when moving downwardly increases the force of the blow against one anvil and when moving upwardly decreases the force of the blow against the other anvil; and counter-balancing means attached to said connection means and operating to exert a

force opposing downward movement and assisting upward movement of the connection means and the piston rod to equalize the blows on each anvil; said counter-balancing means including means for adjusting the counter-balancing force. 5

GEORGE H. HORNE.
